UNITED STATES PATENT OFFICE

ARTHUR M. JERSEY, OF LANSING, MICHIGAN

CAN OPENER

Application filed May 29, 1931. Serial No. 540,978.

The present invention relates to can openers, and more particularly to an opener which is adapted to cut out the top of a tin can and at the same time crimp or turn over that portion of the top remaining on the can.

An object of this invention is to provide a device of this kind which is so constructed that it can be readily used with any type of can, either round in cross section, square or the like.

Another object of this invention is to provide a can opener of this kind which will not leave any jagged edges on either the upper edge of the can or the severed top portion.

A further object of this invention is to provide a device of this kind which can be readily and cheaply manufactured so that it can be produced at a relatively small cost.

The above and various other objects and advantages of this invention will in part be described in and in part be understood from the following detailed description of the present preferred embodiment, the same being illustrated in the accompanying drawing, wherein:

Figure 1 is a detail front elevation of a device constructed according to the preferred embodiment of this invention, showing the manner in which it is used for cutting the top of a can;

Figure 2 is a top plan view of the device, and

Figure 3 is a sectional view partly in detail taken on the line 3—3 of Figure 2.

Referring to the drawing wherein like numerals of reference designate corresponding parts throughout the several views, the numeral 10 designates one handle member which is pivotally secured to another handle member 11 by means of a pivot 13. This handle member 10 is provided adjacent one end thereof with a toothed rotor or disk 12 which is secured to a stem 14 carried by a handle 15.

A bushing or bearing 16 is disposed about the stem 14 and within the handle 10 so as to permit the ready rotation of the wheel 12. The handle 11 is bent intermediate its length, as at 17, and the free or inner end of the handle 11 is reverted, as at 18, and this reverted

portion provided with a cutting member 19 which is provided with a keen edge for engagement with the top of the tin can, so as to sever the top of the can from the side wall thereof. The outer end portion 20 of the reverted member 18 is adapted to engage against the severed portion of the top of the can which remains on the can, so as to bend or crimp this portion of the can against the inner surface of the wall of the can so that no jagged edge will be left after the top of the can has been removed.

In the operation of this device, the toothed wheel 12 is adapted to be disposed on the outer surface of the can 21, and the cutter portion 19 is adapted to be disposed over the top of the can and to engage against the top 22 of the can at the junction of the top 22 with the side wall 21 of the can. In cases where the top of the can is crimped onto the side wall, the cutter 19 will engage the top beneath the crimped portion. The handle or operating member 15 may then be turned so as to rotate the wheel 12, the handles or levers 10 and 11 being disposed in one hand and pressed one toward the other, so that the cutter 19 will pierce or cut the top 22. The rotation of the wheel 12 will move the can about the cutter 19, which movement will at the same time sever the top 22 and crimp the portion of the top 22 which remains on the upper end of the side wall.

Through the provision of the wheel member 12 and the crimping portion 20, the edge of the can will be securely clamped therebetween so that the top 22 may be removed from a can which is relatively hot, in view of the fact that the can may be lifted and held in such position upon closing of the handles 10 and 11 and engagement of the wheel 12 and the crimping portion 20 with the crimped edge of the can.

It will also be obvious that when the top has been completely severed from the can, the top may be removed without releasing the can from between the wheel 12 and the crimping portion 20 so that the contents of the can may be poured out without physically touching the can.

It is, of course, understood that various

changes and modifications may be made in the details of construction and design of the above specifically described embodiment of this invention without departing from the spirit thereof, such changes and modifications being restricted only by the scope of the following claim.

I claim:—

A can opener comprising a pair of pivoted handles, a toothed wheel carried by one of said handles, an operating member for said wheel, and a U-shaped cutting and crimping member formed with the other handle and having the keen edge swingable partially across one face of said wheel, movement of the handles toward each other forcing the cutting member downwardly through the top of the can and coercively clamping the crimped edge of the can between the periphery of the wheel and the closed portion of the cutting member whereby to prevent slipping of the wheel relative to the can and simultaneously moving the crimping portion of the U-shaped member toward the wheel to regulate the crimping of the severed edge remaining on the can.

In testimony whereof I hereunto affix my signature.

ARTHUR M. JERSEY.
